US0D1033635S

(12) **United States Design Patent** (10) **Patent No.:** **US D1,033,635 S**
(45) **Date of Patent:** **** Jul. 2, 2024**

(54) **DERMAL SPRAY NOZZLE**

(71) Applicant: **Kozhya LLC Sp. z o.o.**, Poznań (PL)

(72) Inventors: **Yoanna Gouchtchina**, Allen, TX (US);
Enrique Gallar, Berlin (DE)

(73) Assignee: **Quantum Skin SP Z O.O.**, Poznań (PL)

(**) Term: **15 Years**

(21) Appl. No.: **29/837,826**

(22) Filed: **May 9, 2022**

(51) **LOC (14) Cl.** **24-02**

(52) **U.S. Cl.**

USPC **D24/119**

(58) **Field of Classification Search**

(57) **CLAIM**

The ornamental design for a dermal spray nozzle, as shown and described.

DESCRIPTION

FIG. 1 is a perspective view of top, front, and left sides of a dermal spray nozzle showing our new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines depict portions of the dermal spray nozzle that form no part of the claim.

1 Claim, 7 Drawing Sheets
